J. S. NEWMAN,
TELEPHONE INSTRUMENT.
FILED AUG. 16, 1915.

UNITED STATES PATENT OFFICE.

JOSEPH S. NEWMAN, OF CLEVELAND, OHIO.

TELEPHONE INSTRUMENT.

Application filed August 16, 1915. Serial No. 45,628.

To all whom it may concern:

Be it known that I, JOSEPH S. NEWMAN, a citizen of the United States, residing at Cleveland, in the county of Cuyahoga and

5 State of Ohio, have invented a certain new and useful Improvement in Telephone Instruments, of which the following is a full, clear, and exact description, reference being had to the accompanying drawings.

10 This invention relates to improvements in telephone transmitting instruments and has particular reference to a unique form of carbon cup for use in instruments of this character.

15 The objects are to provide a very simple and economical, yet highly efficient, telephone transmitting instrument that is effective regardless of the angle at which it is held during use.

20 In the attainment of these objects I construct my transmitting instrument of few, simple and inexpensive parts that may be conveniently assembled; the carbon cup comprising a preferably semi-spherical sheet 25 metal shell having its open side flared outwardly to provide a shoulder with which is engaged the periphery of a disk of mica or the like, and these parts are connected preferably by turning the edge of the cup over

30 the edge portion of the disk. A screw of standard type, having a substantially semi-spherical head, is extended through an aperture of the disk and clamped thereto by a nut, the head being disposed upon the inner

35 side of the disk with its convex surface opposed to the concave surface of the cup. Granular conductive material, such as carbon is contained within the cup in sufficient quantity to provide, at all times, regardless 40 of the angle to which the cup is tilted, contact with both cup and screw.

The invention may be broadly defined as consisting of a telephone transmitting instrument comprising a diaphragm having 45 connected to it a pair of opposed electrodes between which is disposed a quantity of granular conductive material, one of said electrodes having a convex surface in opposed relation to a concave surface of the other, the quantity of carbon within the space between said surfaces being such that it is in constant contact with both.

In the accompanying drawing which forms a part hereof, and wherein similar 55 reference characters designate corresponding parts throughout the several views, Fig. 1 is

a central vertical section through a transmitting instrument constructed in accordance with my invention; Fig. 2 is a perspective of the elements of the carbon cup, separated; and Fig. 3 is an enlarged sectional view through the carbon cup, showing the same assembled.

The transmitting instrument A comprises a base 1 which is preferably formed of a 65 circular block of wood having a central aperture 2 for the reception of a tenon 3 that is formed on the lower end of the stem 4 of the instrument. This stem is also preferably made of wood and is formed with a bead 5 at its lower end, and an enlarged upper end 6 that is substantially frusto-conical in shape, thereby to render the stem of artistic design. It will be understood that the shape of the stem will allow it to be readily formed 70 at a slight expense upon a wood turning lathe. A cup-shaped shell 8 has a hole 9 that is applied to a projection 10 rising from the stem 4. The forward or open side of the shell 8 is closed by a cap 11, and between a shoulder 12 thereof and the forward edge of the shell, is clamped the periphery of the metallic diaphragm 13, the cap 11 having a flange 14 which overlies the front of the shell. A funnel shaped mouth-piece 15, having a reduced inner end 16, is applied to the cap 11 by having such reduced end fitted into an aperture 17 of the cap. The mouth-piece has a central opening 18 so that the sound waves introduced into the 80 mouth-piece may have easy access to the diaphragm. This shell, the cap which closes the forward side thereof, and the mouth-piece 15 are preferably made of wood, and may be permanently secured together by 85 gluing the engaging portions thereof. In like manner, the shell 8 may be secured to the stem 4, and the stem 4 to the base 1.

A carbon cup 20 is located within the shell 8 and is connected to the central portion of the diaphragm 13. The cup 20 is pressed from a single piece of metal and is semi-spherical in shape, the wall of the cup being flared outward at its open side to form a shoulder 21 against which the periphery of a disk 22, preferably of mica, may be securely held by crimping the edge 23 of the cup over the exposed surface of the disk, as clearly shown in Fig. 3. This forms a very simple construction for a device of this character. The cup contains a quantity of granular carbon, shown at 25,

and a screw 26 is clamped to the disk 22 by having its head located on the inner side thereof and its body portion extending through an aperture in the disk for the application of a nut 27, between which and the head of the screw, the disk is securely clamped. The screw is then passed through an aperture in the center of the diaphragm 13, and it has applied to its protruding end, a second nut 27. Extending through one side of the shell 8 are two binding posts 28 and 29, the former of which has connection, through the wire 30, with the metallic cup 20, while the binding post 29 is connected, through the wire 31, with the metallic diaphragm 13. The outer ends of these binding posts have the wires E attached to them. It will be observed that the only electrical connection between the diaphragm 20 and the metallic cup is through the particles of the granular carbon 25.

Following the well known principle of transmitting instruments, when the diaphragm 13 is vibrated, the granular carbon in the cup 20 is agitated to vibrate or fluctuate the current which passes therethrough.

Having thus described my invention, what I claim is:—

1. A device of the character set forth comprising a one piece metallic semi-spherical shell having its open side flared outwardly to form a shoulder, a disk of insulating material having its periphery resting upon the shoulder, the edge of the shell being crimped about the outer edge portion of the disk, a substantially semi-spherical headed screw extending through the center of the disk and having its head disposed inside the shell, and granular conductive material contained within the shell in sufficient quantity to be in contact at all times with the shell and screw head regardless of the angular position of the device.

2. A transmitter comprising an open sided shell, a quantity of granular material within the shell, and a plate extending across the open side of and supported solely by the shell and serving to retain the granular material within the shell, the shell and plate being connected together by having the edge of one crimped about the edge of the other.

3. A telephone transmitter comprising a diaphragm and a pair of electrodes connected to and supported solely by the diaphragm, and granular conducting material

between the electrodes, the electrodes having curved surfaces, and the convex surface of one electrode lying opposite to the concave portion of the other electrode for the purpose specified.

4. A telephone transmitter comprising, in combination, a diaphragm, a pair of electrodes connected to and supported solely by the diaphragm, and granular conducting material between the electrodes, the electrodes having one a protruding portion and the other a receding portion, the protruding portion of one electrode, lying opposite to the receding portion of the other, for the purpose specified.

5. A telephone transmitter comprising, in combination, a diaphragm, a pair of electrodes connected to and supported solely by the diaphragm, and granular conducting material between the electrodes, the electrodes being formed on complementary curved surfaces, for the purpose specified.

6. A telephone transmitter comprising a diaphragm and a pair of freely suspended and independently vibratory electrodes in conjunction therewith, connection from the diaphragm to said electrodes, and granular conducting material between the electrodes, the electrodes having curved surfaces, and the convex surface of one electrode lying opposite the concave portion of the other electrode for the purpose specified.

7. A telephone transmitter comprising, in combination, a diaphragm, a pair of freely suspended and independently vibratory electrodes connected thereto, and granular conducting material between the electrodes, said electrodes being formed on complementary curved surfaces, for the purpose specified.

8. A transmitter attachment comprising an inner curved electrode provided with elements for engaging the transmitter, a thin vibratory insulating disc carried by said electrode, an outer curved electrode projecting from the periphery of said disc, said outer electrode surrounding the inner electrode and uniformly spaced from the latter, said electrodes and the said disc combining to form a freely suspended structure having an enclosed curved chamber, and carbon granules deposited within said chamber for maintaining contact between the opposed surfaces of the said electrodes.

In testimony whereof, I hereunto affix my signature.

JOSEPH S. NEWMAN.
